UNITED STATES PATENT OFFICE.

HENRY G. REIST, OF SCHENECTADY, NEW YORK, ASSIGNOR TO THE
GENERAL ELECTRIC COMPANY, OF NEW YORK.

INDUCTION-MOTOR.

SPECIFICATION forming part of Letters Patent No. 678,034, dated July 9, 1901.

Application filed November 28, 1898. Serial No. 697,624. (No model.)

To all whom it may concern:

Be it known that I, HENRY G. REIST, a citizen of the United States, residing at Schenectady, in the county of Schenectady, State of New York, have invented certain new and useful Improvements in Induction-Motors, (Case No. 662,) of which the following is a specification.

The present invention relates to starting and controlling resistances for alternating-current induction-motors and has reference particularly to the means for supporting the same within the revolving member of the motor and to the means for varying the amount of resistance in circuit with the induced winding.

The invention consists more particularly in details of construction and is exemplified in the mechanical arrangement illustrated in the accompanying drawings, in which -

20 Figure 1 is a sectional view of a motor embodying my invention; Fig. 2, a view in end elevation. Fig. 3 is a view of the circuit connections of the induced member, and Fig. 4 is a plan view of the resistance-grid.

25 Referring to the drawings, B denotes the main supporting-frame of an induction-motor of well-known type and having bolted to one side thereof a clamping-plate, B' for so

30 the side thereof a clamping-plate B for securing in place the laminated structure C, forming the core of the inducing member of the motor. A portion of the primary winding is indicated at D. The side plates A are bolted to the supporting-frame B and serve to protect the operating parts of the machine from injury. The side plates A are bolted to the supporting-frame B.

35 from injury. The particular construction of the primary member is, however, immaterial so far as my present invention is concerned.

The revolving or induced member of the motor consists of the usual laminated toothed structure E, supported by end rings G', which in turn are carried by the arms P of the spider secured to the shaft J. The arms of the spider are bolted to the end rings G' by means of lugs G², formed integrally with the drum, as shown in Fig. 2. The end rings are clamped against the laminated core E by bolts. (Not shown.)

50 A portion of the induced winding is shown at F'. The starting resistance connected with this winding is in three sections, as usual, and each section is supported from the inte-

rior of the inducing member by means of a special form of supporting-frame, each frame and associated parts being located between two of the arms P of the spider. This frame 55 consists of a rectangular portion constructed with cross-bars and intervening spaces, so as to give lightness. Stiffening-ribs S are used to give rigidity. A cross-piece T arches over from one side to the other of the supporting-frame and has a forked lug, through which bolts H pass and by which one end of the frame is secured to the ring G'. The opposite end of the supporting-frame is secured by bolts F to lugs formed integral with the 65 ring G', as clearly shown in the drawings. Depending from each supporting-frame are two arms K, connected together by a cross-bar K', formed integral therewith and having extensions projecting therefrom parallel 70 with the main portion of the supporting-frame, as best shown at a, Fig. 1. The U-shaped support thus carried by the depending arms K serves to support the contacts which are electrically connected to the resistance-grid I, carried by the main supporting-frame, as shown in Fig. 1. This resistance-grid I (shown in detail in Fig. 4) consists of a casting having the form of a strip bent back and forth on itself and forming a 80 series of parallel conductors connected in series from one end of the grid to the other. The conductors are shortened at intervals to afford space for certain of the bolts I³, which serve to secure the grid to its supporting-frame. The two outside bolts at one side of the grid pass through the lugs i⁶. These bolts are insulated from the grid, except at the point C, Fig. 1, at which is interposed a metallic washer, which serves to electrically connect 90 one end of the grid to its supporting-frame. The other end of the grid is electrically connected at i⁷ to the lead I², which makes connection with the induced winding in a well-known manner. Intermediate points i⁸ and 95 i⁹ are connected by leads i i' with the contacts i², carried by the depending portion of the supporting-frame and insulated therefrom by plates of insulating material i³. One extremity of the grid is connected through the lead I² with the contact-block I⁴, while the opposite end of the grid is put in connection 100

with the contact-block i^3 through the washer C, the supporting-frame itself, and the bolts b, which are in contact electrically with said contact-blocks and screw into the supporting-frame. Since, however, one end of each resistance-grid is in electrical connection with the frame of the machine, as described, the block i^3 serves less as a contact-block than as a guide for the contact-brush operating in conjunction therewith and hereinafter to be described.

The value of the starting resistance in circuit with the induced member is varied by electrically connecting together corresponding points in each of the three resistances I. In Fig. 3 I have diagrammatically illustrated the circuit connections between the resistance-grids and the winding of the induced member. A plurality of brushes Q, electrically connected to each other and movable over the contacts i^2 and I^4 , serve to control the resistance connections. The brushes Q are carried by a ring R, surrounding the shaft J and movable longitudinally thereon. The ring is prevented from rotating about the shaft by means of the heads of two screws M, so cut away as to form lugs m, which project into and engage the sides of a slot J', formed in the said shaft, as shown clearly in the drawings. In order to allow the screws M to be put in place, the edges of one end of the slot in the shaft J are scooped out or cut away, as shown in section in Fig. 2, so as to receive the heads of the screws and allow the same to be turned. After the screws have been secured in position in the ring R the same is moved along the shaft, so that the lugs m of the screws engage the sides of the slot, and are thus prevented from turning. Movement is communicated to the ring R by means of a cross-bar L, sliding in the slot of the shaft J and having notched ends L' engaging the lugs m, as shown in Fig. 1. The cross-bar L is secured in any suitable manner to one end of a rod K², which slides in a hole J², drilled concentric with the shaft J and extending into the same a distance slightly beyond the slot J². A handle or knob K³ is swiveled to the projecting end of the rod K², so as to allow the rod to turn without turning the knob.

When the entire starting resistance is in

circuit, the brushes and contacts have the relation shown in Fig. 1. When it is desired to cut out the resistance, the rod K² is pushed into the shaft a distance sufficient to cause the brushes Q to connect together the first set of contacts i^2 , thus cutting out approximately half of the resistance. Further movement of the rod K² connects together the middle point of the remaining portion of each resistance, while a still further movement of the rod K² cuts out the resistance entirely by connecting each of the blocks I⁴ together, and thus connecting the leads I² directly to each other.

What I claim as new, and desire to secure by Letters Patent of the United States, is—

1. In an alternating-current motor, the combination of a hollow revolving member, a supporting-frame secured to the interior of the revolving member, a resistance carried by said frame, arms projecting from said frame, contact-blocks carried by said arms and electrical connections between said contact-blocks and resistance.

2. In an alternating-current motor, the combination of a hollow revolving member, a plurality of supporting-frames independently secured to the interior of the revolving member, resistances carried by said supporting-frames, contact-blocks also carried by said supporting-frames and located out of the planes of said resistances, and contact-brushes carried by a device sliding on the shaft of the motor and engaging said contact-blocks.

3. In an alternating-current motor, the combination of a hollow revolving member, a plurality of supporting-frames secured to the interior of said member, resistance-grids mounted on said frames, arms projecting from said frames toward the shaft on which said member is mounted, contacts carried by said arms and electrically connected to said grids, and brushes for said contacts slidingly mounted on the shaft.

In testimony whereof I have hereunto set my hand this 22d day of November, 1898.

HENRY G. REIST.
